US0D1002749S

(12) **United States Design Patent** (10) **Patent No.:** **US D1,002,749 S**
(45) **Date of Patent:** **** Oct. 24, 2023**

(54) **BLOCK**

(71) Applicant: **Tucker Gorman**, Boulder Creek, CA
(US)

(72) Inventor: **Tucker Gorman**, Boulder Creek, CA
(US)

(**) Term: **15 Years**

(21) Appl. No.: **29/890,342**

(22) Filed: **Apr. 22, 2023**

Related U.S. Application Data

(60) Continuation of application No. 29/858,958, filed on Nov. 5, 2022, now Pat. No. Des. 985,681, which is a division of application No. 29/777,178, filed on Apr. 3, 2021, now Pat. No. Des. 974,491.
